US0D1013893S

(12) **United States Design Patent** (10) **Patent No.:** **US D1,013,893 S**
(45) **Date of Patent:** ** *Feb. 6, 2024

(54) **SHOE STERILIZATION DEVICE**

(71) Applicant: **HEPCO HOLDINGS, LLC**, Seminole, FL (US)

(72) Inventors: **Mike Mikurak**, Gulfport, FL (US); **Bryan Scott Beal**, Louisville, KY (US)

(73) Assignee: **HEPCO Holdings, LLC**, Seminole, FL (US)

(*) Notice: This patent is subject to a terminal disclaimer.

(**) Term: **15 Years**

(21) Appl. No.: **29/735,210**

(22) Filed: **May 19, 2020**

(51) **LOC (14) Cl.** 24-04

(57) **CLAIM**

The ornamental design for a shoe sterilization device, as shown and described.

DESCRIPTION

FIG. 1 is a perspective view of a shoe sterilization device showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof showing the shoe sterilization device in an environment; and,

FIG. 9 is another perspective view thereof showing the shoe sterilization device in an environment.

The broken lines depicting an exemplary power cord in FIGS. 1, 3, 4, 5, 6 and 7 form no part of the claimed design. The broken lines depicting screws in FIG. 7 form no part of the claimed design. The broken lines depicting screws in FIGS. 2-5 form no part of the claimed design. The broken lines of FIGS. 8 and 9 depict environmental subject matter only and form no part of the claimed design.

1 Claim, 7 Drawing Sheets
